UNITED STATES PATENT OFFICE.

WILLIAM L. CHURCH, OF NEWTON, MASSACHUSETTS, ASSIGNOR TO AMBURSEN COMPANY, OF BOSTON, MASSACHUSETTS, A CORPORATION OF NEW JERSEY.

DAM.

1,101,785.

Specification of Letters Patent. Patented June 30, 1914.

Application filed October 16, 1913. Serial No. 795,463.

To all whom it may concern:

Be it known that I, WILLIAM L. CHURCH, a citizen of the United States, and a resident of Newton, in the county of Middlesex and State of Massachusetts, have invented 5 a new and useful Improvement in Dams, of which the following is a specification.

The present invention relates to concrete 10 dams of the type described in the patent to Freeman, No. 1,043,761, dated November 5, 1912, in which the decks are formed of a plurality of separately molded concrete beams, supported on buttresses, and the object of my invention is to improve the means 15 for tying the beams to the buttresses in the manner hereinafter set forth.

One embodiment of my invention is shown in the drawings accompanying and 20 forming a part of this specification, in

Figure 1 is a front elevation of the upstream side of a dam embodying my improvement. Fig. 2 is a cross-section of the 25 dam shown in Fig. 1; Fig. 3 is a longitudinal section taken on the line 3—3 of Fig. 1.

In the particular drawings selected for 30 more fully disclosing my invention, 1 represents one of the buttresses formed preferably of concrete; 2 is the heel, 3 the toe, 35 and 4 the crest of a dam constructed preferably of reinforced concrete. The separately-molded beams 5 are supported by the buttresses to form the up-stream deck of the dam, and similar beams 5' 40 constitute the down-stream deck or apron. If desired, the longitudinal corners of the upper surface of each of the beams may be recessed so that a key-way is formed between each abutting pair of beams for receiving cementitious material 6 after the 45 beams are placed in position. It will be understood of course that said key-ways may be dispensed with, and if employed, may have any suitable shape. As shown in Fig. 3, the proximate ends of each pair of beams are shaped to form a key-way, wider 50 at the top than at the bottom, so that a correspondingly-shaped key located in said key-way and attached to a buttress will oppose any upward movement of said beams, and 55 preferably said ends of said beams are beveled, so that the key-way will be wedge-shaped. A tying member 8, such for ex-

ample as a corrugated or twisted metallic rod, is molded in the buttress and has its 55 upper portion projecting through said key-way. Cementitious material is then placed in the key-way and becomes firmly bonded to the proximate ends of the beams and to the tying member, thereby forming a key 7, 60 so shaped as to effectually tie the beams to the buttresses.

It will be understood that various modifications may be made in the particular means hereinbefore described for tying the 65 beams to the buttresses without departing from the spirit of my invention.

I claim:

1. In a dam having a deck consisting of 7 separately molded concrete beams resting at their ends on a buttress, means for tying said beams to said buttress comprising in combination a tying member embedded in said buttress and projecting upwardly into a wedge-shaped key-way formed between 75 the proximate ends of each opposed pair of beams, and cementitious material filling said key-way and inclosing the projecting portion of said tying member.

2. A dam comprising a buttress, a deck 80 consisting of separate beams resting at their ends on said buttress, the proximate ends of each opposed pair of beams being beveled to form a wedge-shaped key-way, a tying member secured to said buttress and projecting upwardly therefrom into said key-way, and a key in said key-way secured to the projecting portion of said tying member. 85

3. In a dam having a deck consisting of 90 separately molded concrete beams resting at their ends on a buttress, means for tying said beams to said buttress comprising in combination a tying member embedded in said buttress and projecting upwardly into 95 a key-way formed between the proximate ends of each opposed pair of beams, said key-way being wider at the top than at the bottom, and cementitious material filling said key-way and inclosing the projecting 100 portion of said tying member.

4. A dam comprising a buttress, a deck 105 consisting of separate beams resting at their ends on said buttress, the proximate ends of each opposed pair of beams being shaped to form a key-way, a tying member secured

to said buttress and projecting upwardly therefrom into said key-way, and a correspondingly shaped key in said key-way secured to the projecting portion of said tying member, said key and key-way being adapted by their shape alone to oppose any upward movement of said beams.

In testimony whereof, I have hereunto subscribed my name this 15th day of Oct. 1913.

WILLIAM L. CHURCH.
